UNITED STATES PATENT OFFICE.

GEORG FORNER, OF BERLIN, GERMANY, ASSIGNOR TO AKTIENGESELLSCHAFT BROWN, BOVERI AND CIE., OF BADEN, SWITZERLAND.

STEAM TURBINE.

Application filed April 19, 1924. Serial No. 707,791.

To all whom it may concern:

Be it known that I, GEORG FORNER, a citizen of the German Republic, residing at Berlin, Germany, have invented certain new and useful improvements in Steam Turbines, of which the following is a specification.

This invention relates to steam turbine velocity stages with slight reaction, and more particularly to a velocity stage wherein a slight expansion takes place within the blading.

Such stages have already been constructed and also described in the literature of the art. In those known stages the reaction is very small and occurs only in the first rings of blades, and is not found in the other rings of blades. That manner of working has very grave drawbacks. In pressure stages having no reaction the relative velocity is considerably greater in the first ring than in the last ring of blades. Consequently the rotor blades of the last ring of blades are much longer than those of the first ring of blades. This however, does not help the designer; the length of the blades in the first ring presents no difficulty to him, and it is the length of the blades in the last row or rows of blades which he would be glad to reduce.

Those drawbacks of the known construction are obviated according to the present invention by arranging for the expansion to take place only in those rings of blades in which the relative entrance velocity is less than the velocity of sound.

This will be correct in most cases only for the last rings of blades. Of particular advantage in this improved connection is the arrangement that the expansion in the blades is carried only to such an extent that the relative exit velocity is less than the velocity of sound. By this means the drawback is avoided that when the velocity of sound is greatly exceeded, the blade passages would have to be constructed in the form of enlarged nozzles if a considerable deflection of the steam jet is not desired. In many cases it is not advantageous to allow the expansion to exceed, in the nozzles, the velocity of sound.

This invention allows the last blades to be made much shorter than in the case of no or only a slight reaction according to the known process, with the result that rotor

friction is diminished, and owing to the smaller divergence of the steam jets a higher efficiency is attained. A further advantage is that the rotor dimensions can be so proportioned that when an alteration occurs in the stage drop, the alteration does not occur in one ring of blades alone or in the nozzles alone, and thus avoids large impact losses.

It is also advisable to distribute the additional expansion drop over the rings of blades that come in question in such a manner that the relative increase in the kinetic energy in the rings of blades is in inverse proportion to the relative entrance velocity. It is advisable to arrange the expansion in the rings of blades in such a manner that the component of the relative exit velocity at right angles to the direction of the peripheral velocity is approximately equal in the rings of blades that come in question.

The accompanying drawings illustrate one way of carrying the invention into effect.

Fig. 1 is a diagram of the pressures in the different stages of known turbines.

Fig. 2 is a velocity diagram corresponding to the same.

Fig. 3 represents diagrammatically the improved turbine in section, through one nozzle, two pairs of rotor blades and one pair of stationary guide blades of the half turbine shown in sectional elevation in Fig. 4.

Fig. 5 is a diagram of the pressures in the different stages of the improved turbine.

Fig. 6 is a velocity diagram corresponding to the same.

In Figs. 1, 3, 4 and 5 of the drawings, A and A' indicate the nozzles for the old and the new arrangement respectively, B, D and B', D' the rotor blades, and C, C' the stationary guide blades.

In Figs. 1 and 5 the lines traversing A, B, C, D and A', B', C', D' represent by their vertical height the comparative pressures in the respective stages.

In the usual constant pressure blading indicated diagrammatically in Fig. 1, the drop of pressure in the nozzle A is completely converted into speed and as the outlet velocity from the nozzle is normally greater than the critical velocity or velocity of sound, the nozzle walls must be so constructed as to diverge. This absolute velocity from the nozzle A is partially converted into work in the first row of rotor blades B. The outlet

velocity from B is also greater than the critical velocity so that the channel between the individual blades of B must also be constructed so as to diverge on the outlet side by suitably profiling the blades. Similarly, the steam passes into the guide blades C and from there to the second rim D of the rotor wheel. Since, in this case, the whole blading works at the same pressure, no energy is supplied, apart from that due to the outlet velocity from the nozzle, so that the velocity decreases not only owing to the output but also owing to the friction in the blades. The result of this is that for the purpose of enlarging the channels for the flow between the blades the outlet angle from the blades must grow continually larger and the radial length of the blades must also substantially increase at the same time.

20. In the present invention, the steam energy in the nozzle is not converted into speed with the full available pressure drop since, as shown in Figures 3 and 4, the nozzle and the blading of the wheel is so dimensioned that 25 in the nozzle A' approximately critical velocity is attained, so that the relative entrance velocity into the first rotor blades lies just below the critical velocity. Naturally, then, the relative exit velocity from this first 30 row of moving blades B' also lies below the critical velocity. The velocity through the reversing row of blades C' decreases again, but according to the present invention a part of the still available pressure drop is to be used in order to bring the velocity up again approximately to the critical velocity. The velocity still remaining in the second row of moving blades D' is increased to a greater extent by the conversion 40 of the remaining pressure drop into velocity, so that this row of blades works also at a velocity that is little below the critical velocity. An enlargement of the nozzle surfaces and possibly of those of the 45 first row of moving blades B' and a diminishing of the exit surface of the reversing guide blade C' and of the second blade rim D' is made in conjunction with the decrease in the exit velocity from the nozzles A' and 50 the subsequent increase in the velocities in the reversing guide blade C' and the second row of moving blades D'. The radial dimensions of the nozzles A' and possibly of the first ring of blades B' is therefore greater 55 in the proposed blading than in the usual constant pressure blading and, on the other hand, the blading of the reversing guide blade C' and of the second rim D' is smaller.

60. In the usual constant pressure turbine stage, known as a velocity stage, the whole pressure energy of the working steam is con-

verted in the nozzle alone to the full speed O—P. In the first rotor rim the steam velocity is reduced to the relative entrance velocity O—Q and again reduced by the 65 losses in the blade to the relative outlet velocity O—R.

Similarly for the reverse segment or guide blade ring I get the absolute entrance velocity O—S and absolute exit velocity O—T, 70 and lastly for the second rotor rim the relative velocity at the entrance O—U and the relative velocity at the outlet O—V or the absolute outlet velocity O—W.

In view of the fact that during the whole 75 operation no more energy is supplied, the said velocities continually decrease.

In the blading according to the invention, in addition to the conversion of the major portion of the available pressure energy of the steam into the velocity O'—P', a moderate conversion also takes place in the individual blades. The velocities O'—R', O'—S', O'—T', O'—U', O'—V' and O'—W' therefore decrease much less and in 85 consequence the blading may be made of smaller radial dimensions.

What I claim is:—

1. A steam turbine velocity stage with slight reaction, in which the reaction effect 90 takes place only in the last blades in which the relative entrance velocity is smaller than the so-called critical velocity.

2. A steam turbine velocity stage as 95 claimed in claim 1, wherein the expansion in the blades is carried only to such a degree that the relative exit velocity is smaller than the velocity of sound.

3. A steam turbine velocity stage as 100 claimed in claim 1, wherein the nozzles are in the form of non-enlarged guide devices, the expansion in these nozzles being carried only to such a degree that the velocity of outflow from them is approximately equal to the velocity of sound.

4. A steam turbine velocity stage as 105 claimed in claim 1, wherein the relative comparative proportional increase in the kinetic energy in the blades is greater the smaller the relative entrance velocity.

5. A steam turbine velocity stage as 110 claimed in claim 1, wherein on the occurrence of an alteration in the stage drop, this alteration has effect in more than one ring of blades.

6. A steam turbine velocity stage as 115 claimed in claim 1, wherein the axial component of the exit velocity is approximately the same in all the rings of blades.

In testimony whereof I have signed my 120 name to this specification.

GEORG FORNER.
